UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

ENGINE GANG-PLOW.

1,084,081.

Specification of Letters Patent.

Patented Jan. 13, 1914.

Application filed May 21, 1913. Serial No. 768,943.

To all whom it may concern:

Be it known that I, WILLIAM S. GRAHAM, a citizen of the United States, residing at Canton, in the county of Fulton, in the State of Illinois, have invented certain new and useful Improvements in Engine Gang-Plows, of which the following is a specification, reference being had to the accompanying drawings.

This invention relates to engine gang plows and has for its object the provision of new and improved means for lifting the plows successively when desired as the plow is being drawn forward whereby the several furrows shall end substantially at a line extending at right angles to the direction of progress of the plow.

It is another object of this invention to provide means which may be thrown into operation as desired by the operator for automatically lowering the plows in succession whereby the furrows opened by the several plows may begin substantially at a line at right angles to the direction of progress of the plow.

It is another object of my invention to improve devices of this type in sundry details hereinafter pointed out.

The means by which I have accomplished these objects are illustrated in the drawings and are hereinafter specifically described.

That which I believe to be new is set forth in the claims.

In the drawings, Figure 1 is a top or plan view of a plow embodying my improvements, only two of the several plow-beams being shown; Fig. 2 is a side view of the plow shown in Fig. 1, with one plow beam in raised position, the other plow beam and one of the frame-supporting wheels being omitted for clearness of illustration; Fig. 3 is a side view of the parts shown in Fig. 2, but showing the beam in its lowered position; Fig. 4 is an enlarged detail being a section taken on line 4-4 of Fig. 1, but with the parts in a changed position; Fig. 5 is an enlarged detail being a central vertical section through one of the lifting arms mounted on the main drive-shaft; Fig. 6 is an enlarged detail of the parts shown in Fig. 4 at still another phase of their operation; Fig. 7 is an enlarged detail being a diagrammatic view showing the relative positions of the several lifting arms

carried by the main drive-shaft; Fig. 8 is an enlarged detail being a diagrammatic view showing the relative positions of the arms by which the beams are successively released from their raised positions; Fig. 9 is an enlarged detail being a top plan view of one end of the frame in which the main driving shaft is mounted, showing the clutch mechanism by which said shaft is connected to the driving means; Fig. 10 is a section taken on line 10-10 of Fig. 9; Fig. 11 is a section taken on line 11-11 of Fig. 9; Fig. 12 is a section taken on line 12-12 of Fig. 9; Fig. 13 is an enlarged detail being substantially a section on line 13-13 of Fig. 12; and Fig. 14 is an enlarged detail being substantially a section on line 14-14 of Fig. 12.

Referring to the several figures of the drawings in which corresponding parts are indicated by the same reference characters, 20 indicates the framework of the plow comprising a diagonal beam 21 to which the plow beams are adapted to be attached.

22 indicates a chain secured to the forward end of the frame 20 by which the plow is adapted to be connected to an engine or other suitable means by which it may be drawn forward.

23 indicates a caster-wheel pivotally mounted at the forward end of the frame 20.

24 indicates a supporting wheel revolvably mounted upon the frame 20 in any suitable manner.

25 indicates a bracket fixedly secured upon the diagonal beam 21, upon the rear edge of which a plow-beam comprising bars 26-27 is pivotally mounted in any suitable manner.

28 indicates a plow-share mounted in any suitable manner upon the rear ends of the beams 26-27.

29 indicates a circular rack secured at its lower end to the beams 26-27 by means of a bracket 30 and secured at its upper end by means of bars 31-32 which are connected to the bars 26-27, respectively, by means of brackets 33-34.

35 indicates a lever pivotally mounted on a bolt 36 extending between the brackets 33-34, said lever being provided with a spring-seated detent 37 and latch 38 for operating it, of any suitable well-known type, whereby the lever can be set and held in any

of a plurality of positions about the pivot bolt 36. 39 indicates a bell-crank lever also pivotally mounted upon the bolt 36.

40 indicates a gage-wheel revolvably mounted upon the lower turned end of a bar 41, the other turned end of which is pivotally mounted in a bracket 42 depending from the plow-beams 26-27.

43 indicates a link pivotally connected at 10 its upper end to the forwardly-extending arm of the bell-crank lever 39 and pivotally connected at its lower end to a bracket 44 carried by the lower end of the bar 41.

As will be readily understood, when the 15 bell-crank lever 39 is swung forward in clockwise direction in Figs. 2 and 3 the beams 26-27 and the plow-share 28 will be raised relative to the gage-wheel 40. It will likewise be understood that the lever 35 is 20 adapted to be swung in clockwise direction in said figures upon its pivot 36 to hold the bell-crank lever 39 in its turned position through the medium of a bracket 45 which is adapted to contact a stop 46 mounted on 25 the forwardly-extending arm of said bell-crank lever. It will be understood moreover that by a stroke of the lever 35 the bell-crank lever may be turned for the purpose of raising the plow-beam independently of 30 any other instrumentality. It will be understood that when the plow-share is standing in raised position, being held in such position either by the lever 35 or by the means hereinafter described for operating 35 upon said bell-crank, upon the releasing of the lever 35 or said other means for operating the bell-crank the beams 26-27 and the plow 28 will through their own weight drop to their lowermost position. It will be understood that the lever 35 is adapted to be 40 set to regulate the extent to which the bell-crank lever can move in counterclockwise direction, thus limiting the depth to which the plow-share is adapted to run.

45 47-48 indicate the cross-bars of the frame in which is journaled the main drive-shaft 49 of the means for raising the plows by power.

50 50 indicates the end bar of said frame, 50 which, as best shown in Fig. 12, is in the form of a channel-iron opening inwardly.

51-52 indicate a plurality of pairs of frame-bars extending from one to the other of said bars 47-48 as best shown in Fig. 1.

55 53 indicates angle-irons, as best shown in Fig. 1, by which the bar 48 is secured to the frame 20 of the plow.

As best shown in Fig. 1, the frame-bars 51-52 are for the greater portion of their 60 length spaced away from each other, being adapted to be connected to each other by means of bolts 54.

55-56 indicate levers pivotally mounted by means of bolts 57 to the frame-bars 65 51-52, respectively, said levers being curved

so as to permit of their being turned down over the shaft 49 as shown in Fig. 6. The pivoted ends of the levers 55-56 are spaced apart from each other for the passage between them of the lifting arms mounted on the main drive-shaft 49 as hereinafter described. The free ends of the levers 55-56 are connected together by means of bolts 58 so as to cause said levers to swing in unison.

59 indicates a roller revolvably mounted by 75 means of a pin 60 between the ends of the levers 55-56.

61 indicates a latch pivotally mounted by means of a pin 62 between each pair of levers 55-56, adapted to be held normally by 80 a spring 63 in contact with stops 64 mounted on said levers 55-56.

65 indicates a hook formed on the free end of the latch 61 adapted to coöperate with the shoulder 66 formed in the bars 51-52 for 85 holding the levers 55-56 in the position shown in Fig. 4.

67 indicates a link, the turned forward end of which extends through a suitable opening in the forward end of the lever 55, as best 90 shown in Figs. 2 and 3, the rear end of which link is connected to a chain 68 which passes under a pulley 69 revolvably mounted by means of a bracket 70 upon the plow-beam 27. The rear end of the chain 68 is 95 connected to the front end of a link 71, the rear turned end of which is pivotally connected to the end of the upwardly extending arm of the bell-crank lever 39. The connection between the bell-crank lever 39 and the lever 55 is such that when the levers 55-56 are turned backward in the position shown in Figs. 3 and 6 the bell-crank lever 39 is permitted to swing in counterclockwise direction in Fig. 3 so as to permit the plow-beams 26-27 to have their lowermost position, unless, of course, such swinging of the bell-crank lever 39 is prevented by the lever 35 as above explained. When, however, the levers 55-56 are turned forward as shown 110 in Figs. 2 and 4 the bell-crank lever 39 is caused to move in clockwise direction as shown in Fig. 2 raising the plow-beams 26-27 and withdrawing the plow-share 28 from the ground.

In order to bring about the successive raising of the plow-beams pivotally mounted upon the diagonal beam 21 as above described, means is provided for turning the pairs of levers 55-56 successively into their forward positions. It will be understood, of course, that each pair of levers 55-56 is adapted to be connected by means of a link 67, chain 68 and link 71 to the bell-crank lever 39 of the plow-beam immediately in rear of 120 such levers 55-56, each of the plow-beams being provided with a gage-wheel 40 and lifting means of the type described hereinabove.

Coming now to the means for successively 130

swinging the pairs of levers 55—56 forward for raising the plow-beams into their uppermost position where they are held by the latches 61 which automatically engage the shoulders 66 of the bars 51—52, 72—73—74—75 indicate arms mounted upon the squared shaft 49 between the bars 51—52, each of said arms being mounted upon said shaft by means of a hub-portion 76 which extends from one to the other of the bars 51—52 centering the arm between said bars and spacing the arm a distance therefrom at each side. As best shown in Fig. 7, the arms 72—73—74—75 are spaced about the shaft 49 at an angle to each other so that when the shaft is turned in a clockwise direction as shown in Fig. 7 the arms are brought successively into operative position. The arm 72 of the raising means for the foremost plow is adapted to stand normally in the position of the arm shown in Fig. 6, lightly in contact with the roller 59 of its pair of levers 55—56. Upon a rotation of the shaft 49 in clockwise direction as shown in Figs. 6 and 7, the arm 72 causes the roller 59 of the levers 55—56 by which the foremost plow is raised to move upward, swinging said levers 55—56 upward and forward, starting the operation of raising the foremost plow. Shortly thereafter the arm 73 is brought in contact with the roller 59 of the next succeeding pair of levers 55—56, starting the operation of raising the second plow. Successively thereafter the remaining lifting arms are brought into contact with the rollers 59 of the remaining pairs of levers 55—56 whereby the plows are raised in succession, the foremost plow first and the rearmost plow last, the arrangement of the arms 72, 73, 74, 75, etc., being such that all of the plows are raised at substantially the same point relative to the forward movement of the plow,—that is to say at a line at right angles to the progress of the plow. As each plow reaches its uppermost position the latch 61 engages the corresponding shoulder 66 locking all of the plows in raised position.

Coming now to the means for releasing the plows to permit them to drop successively on a line at right angles to the forward movement of the plow, 77 indicates a shaft revolvably mounted in the framework in advance of the shaft 49. As best shown in Fig. 8, 78—79—80—81 indicate arms mounted upon the shaft 77 at an angle to each other, the angle between successive arms 78—79—80—81 corresponding to the angle between the arms 72—73—74—75 upon the shaft 49. Each of the arms 78—79—80—81 is mounted between two of the bars 51—52 and is provided at its free end with a roller 82. The roller 82 of the arm 78 normally stands substantially in contact with the heel of the latch-lever 61 by which

the foremost plow is held in raised position,—that is to say, of course, when the levers 55—56 are in their foremost position as illustrated in Fig. 2. With all of the plows held in raised position by means of the latches 61 and with the levers 35 in position to permit the lowering of the plow-beams, a rotation of the shaft 77 in counterclockwise direction causes the roller 82 of the arm 78 to release the latch 61 of the first pair of levers 55—56 permitting the foremost plow to drop into operative position. Shortly thereafter as the shaft 77 continues to rotate the roller 82 of the arm 79 releases the latch 61 of the second pair of levers 55—56 permitting the second plow to drop, and at intervals thereafter each of the plows is likewise released, the arrangement of the arms 78, 79, 80, 81, etc., being such that as the shaft 77 continues to rotate in counterclockwise direction as driven by the forward progress of the plow, the plow-shares 28 drop at the same relative point,—that is to say at a line at right angles to the progress of the plow.

Referring to Fig. 5 which shows in detail one of the arms 72—73—74—75, 83 indicates a bracket formed with and extending from one side of the hub 76, said bracket comprising a main web 84 and two flanges 84^a at opposite sides of said web 84. 85 indicates a block inserted in said bracket 83, said block having a curved exterior surface along which the roller 59 is adapted to roll as the arm forces the levers 55—56 upward and forward. 86 indicates a set-screw mounted in the block 85 adapted to limit the movement of said block toward the hub 76. 87 indicates a set-screw mounted in the block 85 and passing through a slot 88 in the web 84, said set-screw 87 being adapted to clamp the block 85 in adjusted position in said bracket 83. As best shown in Fig. 6 each of the arms 78—79—80—81 is cut out at its central portion for the reception of the roller 82 which is revolvably mounted thereon by means of a pin 89.

Coming now to the means for driving the shafts 49 and 77 as desired, the shaft 49 in clockwise direction and the shaft 77 in counterclockwise direction, as shown in Figs. 2 and 3, 90 indicates a drive-wheel mounted upon an axle 91 carried by the frame 20. 92 indicates a sprocket-gear mounted concentrically with the wheel 90 and adapted to rotate therewith. 93 indicates a sprocket-chain connecting the sprocket-gear 92 with sprocket-teeth 94 mounted upon the periphery of the clutch-wheel 95 revolvably mounted by means of a hub 96 upon the rounded end of the shaft 49. As best shown in Fig. 12 the clutch-wheel 95 comprises two clutch members 97—98, each of which consists of a circumferential flange evenly grooved on its inner periphery.

99 indicates a collar squared in cross-section secured in position upon the squared shaft 49 by means of a set-screw 100.

101 indicates a bracket (see Figs. 10 and 14) formed with the collar 99, one end of said bracket being cut out in circular form to receive a circular roller as hereinafter described.

102 indicates an arm pivotally mounted by means of a pin 103 upon the bracket 101.

104 indicates a roller revolvably mounted upon the arm 102 adapted normally to pass into engagement with one of the grooves of the clutch member 97, as best shown in Fig. 14, such engagement being effected through the medium of a spring 105 attached to one end of the arm 102 and to the bracket 101. 106 indicates a lever pivotally mounted by means of a bracket 107 upon the rounded end of the shaft 77, said lever being normally held against swinging in a clockwise direction as shown in Fig. 10 by means of a spring 108 mounted as hereinafter described.

109 indicates a roller revolvably mounted upon the upper end of the bracket 107, adapted to engage the notched or rounded out end of the bracket 101. As best shown in Fig. 10 when the lever 106 is held by the spring 108 in its extreme turned position the roller 109 serves not only to engage the end of the bracket 101 but also engages the end of the arm 102 holding said arm turned upon its pivot 103 against the action of the spring 105 so as to hold the roller 104 out of engagement with the grooves in the inner periphery of the clutch member 97. When, however, the lever 106 is swung in clockwise direction as shown in Fig. 10 the arm 102 is turned through the medium of the spring 105 upon the pivot pin 103 causing the roller 104 to engage one of the grooves of the clutch member 97 whereby the rotation of the clutch-wheel 95 in clockwise direction in said Fig. 10, as it is driven from the wheel 90 in the forward progress of the plow, causes the shaft 49 also to rotate in clockwise direction in said figure as will be readily understood. When the bracket 101

50 has been turned out of the position in which the roller 109 is adapted to engage said bracket the lever 106 is held against undue rotation in counterclockwise direction upon the shaft 77 by means of a lug 110 on the bracket 107 coming in contact with the transverse frame-bar 48. When the bracket 101 has been given a complete rotation with the clutch-wheel 95, the bracket 101 again assumes the position shown in Fig. 10, the roller 109 riding up the forward edge of the end of the bracket 101 turning the lever 106 against the action of the spring 108 until the roller 109 is permitted to engage the rounded out or notched end of said bracket 101, by which engagement the arm 102 is swung

against the action of the spring 105 rocking the roller 104 out of engagement with the groove of said clutch member 97.

111 indicates a sleeve revolvably mounted upon the hub 96 of the clutch-wheel 95 held in position thereon by the frame-bar 50.

112 indicates a gear mounted on one end of the sleeve 111, in the construction shown said gear being cut directly in the end of said sleeve.

113 indicates a gear keyed or otherwise fixedly mounted upon the end of the shaft 77, said gear 113 being driven from said gear 112 through the medium of gears 114-115 interposed therebetween, said gears 114-115 being mounted upon stub-shafts 116-117, respectively, suitably mounted in the frame-bar 50. As will be seen from Fig. 9 the channel-iron frame-bar 50 incloses the gears 114-115-113 serving as a housing for the protection of said parts, this arrangement serving also to materially economize space without sacrificing strength.

118 indicates a bracket (see Figs. 11 and 13) formed with the sleeve 111, the outer end of said bracket being rounded out for the reception of a roller 119 hereinafter referred to.

120 indicates an arm pivotally mounted by means of a pin 121 upon the bracket 118, said arm 120 having revolvably mounted upon it a roller 122 adapted normally to engage one of the peripheral grooves of the clutch member 98, such normal engagement between the roller 122 and the clutch member 98 being secured by means of a spring 123 connecting one end of the arm 120 to the bracket 118.

124 indicates a lever pivotally mounted by means of a bracket 125 upon the rounded end of the shaft 77. The bracket 125 has the roller 119 revolvably mounted upon it, said roller while in engagement with the rounded end of said bracket 118 serving to hold the arm 120 turned in clockwise direction relative to the bracket 118 in Fig. 11 against the action of the spring 123 holding the roller 122 out of contact with the grooved clutch member 98, the lever 124 being normally held in the position shown in said Fig. 11 through the medium of the spring 108 as hereinafter described. As will be readily understood, with the clutch-wheel 95 being rotated in counterclockwise direction in Fig. 11 by its connection with the drive-wheel 90, and with the parts in the position shown in said figure, the shaft 77 is not in rotation. When the lever 124, however, has been given a stroke in counterclockwise direction in said figure so as to free the roller 119 from the bracket 118 and the arm 120 the roller 122 is brought by the spring 123 into engagement with one of the grooves of the clutch member 98 causing the bracket 120 and the sleeve 111 to rotate with said clutch-wheel in coun-

terclockwise direction in said figure, serving to drive the shaft 77 in clockwise direction in said figure. When the bracket 118 has been moved out of position in which it may be engaged by the roller 119 the lever 124 is held against undue rotation in clockwise direction in Fig. 11 by means of the lug 126 on the bracket 125 being brought in contact with the transverse frame-bar. When the bracket 118 makes substantially a complete rotation with the clutch-wheel 95 the roller 119 carried by the lever 124 rides up the forward edge of the bracket 118 as said bracket is rotated and assumes again engagement with the rounded cut or recessed end of said bracket, forcing the arm 120 in clockwise direction in Fig. 11 against the action of the spring 123, freeing the roller 122 from engagement with the groove of the clutch member 98.

127—128 indicate cords attached at their rear ends to the levers 106—124, respectively. It will be understood that by a forward pull upon the cord 127 by an operator the clutch member 97 becomes operative to cause one complete rotation of the shaft 49 in clockwise direction in Figs. 2 and 3 causing the plows to be successively raised if before the actuation of the lever 106 by the cord 127 the plows were in lowered position. It will be understood that when the plows are held in raised position a forward pull upon the cord 128 serves to operatively connect the clutch-wheel 95 through the clutch member 98 with the shaft 77 to cause a complete rotation of said shaft in counterclockwise direction in Figs. 2 and 3 for releasing the plows successively from raised position as hereinbefore described.

129 indicates a cross-bar extending from one to the other of the brackets 107—125 of the levers 106—124, with the ends of said cross-bar extending through suitable openings in the lower ends of said brackets.

130 indicates a bracket extending forward from the transverse frame-bar 48 opposite the middle point of the cross-bar 129, the spring 108 before referred to being connected at its rear end to the middle point of the cross-bar 129 and at its other end to the front end of the bracket 130.

By the expedient of mounting the arms 72—73—74—75 between the ends of the levers 55—56 when in their rearmost position, I secure a construction in which the roller 59 during the first portion of the raising operation, at which time the greatest power is required for starting the plow from the ground, contacts its arm 72—73—74—75 at substantially the same point quite close to the axis of rotation of the shaft 49, the action being almost purely a lifting action with scarcely any friction. After the plow is practically clear of the ground and the heavy lifting has been accomplished, the

roller 59 gradually approaches the end of the curved operative face of the lifting arm with the consequent more rapid turning of the levers 55—56.

What I claim as my invention and desire to secure by Letters Patent, is—

1. In a gang plow, the combination of a frame, two shafts revolubly mounted thereon, a plow-beam pivotally mounted thereon, a plow carried by said plow-beam, a power-driven integral clutch device comprising two clutch members, means for connecting one of said clutch members with one of said shafts for rotating the shaft, means connecting said shaft with the plow-beam for raising the plow-beam, means for holding said plow-beam in raised position, means for connecting the other of said clutch members with the other of said shafts for rotating it, and means actuated by the rotation of said last-named shaft for releasing said plow-beam from its raised position.

2. In a gang plow, the combination of a frame, two shafts revolubly mounted thereon, a plow-beam pivotally mounted thereon, a plow carried by said plow-beam, a power-driven clutch device comprising two clutch members on one of said shafts, means for connecting one of said clutch members with one of said shafts for rotating the shaft, means connecting said shaft with the plow-beam for raising the plow-beam, means for holding said plow-beam in raised position, means for connecting the other of said clutch members with the other of said shafts for rotating it, and means actuated by the rotation of said last-named shaft for releasing said plow-beam from its raised position.

3. In a gang plow, the combination of a frame, two shafts revolubly mounted thereon, a plow-beam pivotally mounted thereon, a plow carried by said plow-beam, two clutch members revolubly mounted on said frame, a gear, connections between said gear and said two clutch members whereby the gear is adapted to rotate said clutch members, means for driving said gear, means for connecting one of said clutch members with one of said shafts for rotating the shaft, means connecting said shaft with the plow-beam for raising the plow-beam, means for holding said plow-beam in raised position, means for connecting the other of said clutch members with the other of said shafts for rotating it, and means actuated by the rotation of said last-named shaft for releasing said plow-beam from its raised position.

4. In a gang-plow, the combination with a frame, two shafts revolubly mounted thereon, and a pivoted plow-beam carrying a plow, of a power-driven clutch device having two separate clutch members, means

- for connecting each of the shafts with one of said clutch members to rotate the shafts in opposite directions, means for connecting one of said shafts with said plow-beam for 5 raising the beam, and means actuated by the rotation of the other of said two shafts for releasing said beam from raised position.
5. In a gang-plow, the combination with a frame, two shafts revolubly mounted thereon, and a pivoted plow-beam carrying a plow, of power-driven clutch mechanism, means for operatively connecting said clutch mechanism with one of said shafts to rotate it, means comprising a plurality of gears for 10 operatively connecting the said clutch mechanism with the other of said shafts to rotate it in the opposite direction from the first-named shaft, means for connecting one of said shafts with said plow-beam for 15 raising the beam, and means actuated by the rotation of the other of said two shafts for releasing said beam from raised position.
6. In a gang-plow, the combination of a frame, two shafts revolubly mounted thereon, a plow-beam pivotally mounted on said frame, a plow carried by said plow-beam, two clutch members revolubly mounted on one of said shafts, means mounted on said shaft for rotating said two clutch members 20 in unison, means for connecting one of said clutch members with one of said shafts for rotating the shaft, means connecting said shaft with the plow-beam for raising the plow-beam, means for holding said plow-beam 25 in raised position, means for connecting the other of said clutch members with the other of said shafts for rotating it, and means actuated by the rotation of said last-named shaft for releasing said plow-beam 30 from its raised position.
7. In a gang-plow, the combination of a frame, a plow-beam pivotally mounted on said frame, a plow carried by said plow-beam, a shaft revolubly mounted on said 35 frame, means for connecting said shaft with said plow-beam for raising the beam, means for holding said beam in raised position, a second shaft revolubly mounted on said frame, means actuated by the rotation of 40 said second shaft for releasing said plow-beam from its raised position, two clutch members revolubly mounted on one of said shafts, means for driving in unison said two clutch members, a third clutch member revolubly mounted on said shaft, a fourth clutch member mounted on said shaft and connected thereto and adapted to rotate therewith, means for throwing into and out of 45 operative connection one of said first-mentioned two clutch members and said fourth clutch member for rotating said first-mentioned shaft, means for throwing into and out of operative connection the other of said first-mentioned two clutch members and said third clutch member, and means operatively connecting said third clutch member with said second shaft for rotating it.
8. In a gang-plow, the combination of a frame, a plow-beam pivotally mounted on said frame, a plow carried by said plow-beam, a shaft revolubly mounted on said frame, means for connecting said shaft with said plow-beam for raising the beam, means for holding said beam in raised position, a second shaft revolubly mounted on said frame, means actuated by the rotation of 50 said second shaft for releasing said plow-beam from its raised position, two clutch members revolubly mounted on said shaft, a gear revolubly mounted on said shaft, means for driving said gear, said gear and said two clutch members being connected whereby the gear is adapted to rotate said clutch members in unison, a third clutch member revolubly mounted on said first-mentioned shaft, a gear revolubly mounted on said shaft, means for driving said gear, said gear and said two clutch members being connected whereby the gear is adapted to rotate said clutch members in unison, a third clutch member revolubly mounted on said first-mentioned shaft, a fourth clutch member mounted on said shaft and connected thereto and adapted to rotate therewith, means for throwing into and out of operative connection one of said first-mentioned two clutch members and said fourth clutch member for rotating said first-mentioned shaft, means for throwing into and out of operative connection the other of said first-mentioned two clutch members and said third clutch member, and means operatively connecting said third clutch member with said second shaft for rotating it.
9. In a gang plow, the combination of a frame, a plow-beam pivotally mounted thereon, a plow carried by said plow-beam, two shafts revolubly mounted in said frame, a clutch member revolubly mounted on one of said shafts, another clutch member adapted to operatively engage said first-named clutch member, a train of gears connecting the other of said shafts with said second-named clutch member, said frame comprising a channel iron end member in which said gears are mounted, means for raising said plow-beam, and means actuated by the rotation of said last-mentioned shaft for releasing said plow from raised position.
10. In a gang plow, the combination of a frame comprising an end member in the form of a channel iron, a plow-beam pivotally mounted thereon, a plow carried by said plow-beam, two shafts revolubly mounted in said frame, a power-driven integral clutch device comprising two clutch members revolubly mounted on one of said shafts, means for connecting one of said clutch members with the shaft upon which it is mounted for causing a rotation of said shaft, means actuated by the rotation of said shaft for raising said plow-beam, means

- for connecting the other of said clutch members with the other of said shafts, and means actuated by the rotation of said last-named shaft for releasing said plow-beam 5 from raised position, the means for connecting said last-named shaft with its clutch member comprising a plurality of gears mounted in the channel iron end member of said frame.
- 10 11. In a gang-plow, the combination of a frame, a plow-beam pivotally mounted thereon, a plow carried by said plow-beam, a lever pivotally mounted on said frame, connections between said lever and said 15 plow-beam, and an arm rotatably mounted in an offset between the ends of said lever with the plow in its normal lowered position, said arm by its rotation being adapted to actuate said lever for raising said plow.
- 20 12. In a gang-plow, the combination of a frame, a plow-beam pivotally mounted thereon, a plow carried by said plow-beam, a lever pivotally mounted on said frame for raising said plow-beam, and an arm rotatably mounted adjacent to said lever adapted to be revolved in contact with said lever for actuating it, said arm comprising a removable bearing block having contact with said lever.
- 25 13. In a gang-plow, the combination of a frame, a plow-beam pivotally mounted thereon, a plow carried by said plow-beam, a lever pivotally mounted on said frame for raising said plow-beam, and an arm rotatably mounted adjacent to said lever adapted to be revolved in contact with said lever for actuating it, said arm comprising a bracket 35 in the form of a channel iron and a bearing block removably mounted therein.
- 30 14. In a gang plow, the combination of a frame, a plow-beam pivotally mounted thereon, a plow carried by said plow-beam, a shaft revolvably mounted in said frame, a curved lever pivotally mounted eccentrically 40 of said shaft adapted to be turned down about said shaft, and an arm mounted on said shaft adapted to engage said lever to swing the lever for raising said plow-beam, said arm being adapted to exert its greatest 45 power upon said lever at the start of the raising operation.
- 45 15. In a gang plow, the combination of a frame, a plow-beam pivotally mounted thereon, a plow carried by said plow-beam, two shafts revolvably mounted in said frame, 50 a curved lever eccentrically mounted relative to one of said shafts and adapted to be swung down to embrace said shaft, an arm mounted on said shaft adapted to engage 55 said lever to swing it for raising said plow-beam, said arm being adapted to exert its greatest power upon said lever at the start of the raising operation, a latch adapted to engage and hold said lever in turned posi-
- tion, and an arm on the other of said two 65 shafts adapted to be revolved into engagement with said latch to release the same.
16. In a gang plow, the combination of a frame, a plow-beam pivotally mounted thereon, a plow carried by said plow-beam, 70 a lever pivotally mounted on said frame for raising said plow-beam, an anti-friction roller revolvably mounted on said lever, and an arm rotatably mounted between the axis of said lever and said roller when the plow 75 is in normal lowered position, said arm being adapted to be revolved into engagement with said roller for actuating said lever, the engaging face of said arm being curved rearwardly in the direction of its rotation 80 whereby power is applied gradually from said arm to said lever.
17. In a gang plow, the combination of a frame, a plow-beam pivotally mounted thereon, a plow carried by said plow-beam, 85 a lever pivotally mounted on said frame for raising said plow-beam, an anti-friction roller revolvably mounted on said lever, an arm eccentrically mounted relative to said lever adapted to be revolved into engagement with said roller for actuating said lever, 90 the engaging face of said arm being curved rearwardly in the direction of its rotation whereby power is applied gradually from said arm to said lever, and means for 95 adjusting the effective length of said arm.
18. In a gang plow, the combination of a frame, a plow-beam pivotally mounted thereon, a plow carried by said plow-beam, a pair of levers spaced apart and pivotally 100 mounted on said frame for raising said plow-beam, a roller revolvably mounted between said levers, and an arm rotatably mounted substantially in line between the axis of said levers and said roller with the 105 plow in its normal lowered position, said arm being adapted by its rotation to move said roller out of substantial alinement with the axes of said arm and said levers for raising the plow.
19. In a gang plow, the combination of a frame, a plow-beam pivotally mounted thereon, a plow carried by said plow-beam, a pair of levers spaced apart and pivotally 110 mounted on said frame for raising said plow-beam, a roller revolvably mounted between said levers, an arm rotatably mounted between the axis of said levers and said roller when the plow is in 115 normal lowered position, said arm being adapted to be moved between said levers to engage said roller to actuate said levers, and a latch-lever adapted to hold said first-named levers against reverse movement after the raising of said plow-beam.
20. In a gang plow, the combination of a frame, a plow-beam pivotally mounted thereon, a plow carried by said plow-beam,

a pair of levers spaced apart and pivotally mounted on said frame for raising said plow-beam, a roller revolubly mounted between said levers, an arm rotatably mounted 5 between the axis of said levers and said roller when the plow is in normal lowered position, said arm being adapted to be moved between said levers to engage said roller to actuate said levers, latch-levers pivotally 10 mounted on said first-named levers adapted to engage the frame to hold said first-named levers against reverse movement, and means for releasing said latch-levers.

21. In a gang-plow, the combination of 15 a frame, a plow-beam pivotally mounted thereon, a plow carried by said plow-beam, a shaft revolubly mounted in said frame, a double clutch member revolubly mounted relative to said shaft, means for revolving 20 said double clutch member, a second clutch member non-revolubly mounted relative to said shaft adapted to be thrown into engagement with said double clutch member whereby said shaft is driven, a third clutch 25 member revolubly mounted relative to said shaft and relative to said double clutch member adapted to be thrown into engagement with said double clutch member, means actuated by the rotation of said shaft for rais- 30 ing said plow-beam, and means actuated

by the rotation of said third clutch member for releasing said plow-beam from its raised position.

22. In a gang-plow, the combination of a frame, a plow-beam pivotally mounted thereon, a plow carried by said plow-beam, a shaft revolubly mounted in said frame, a double clutch member revolubly mounted relative to said shaft, means for revolving said double clutch member, a second clutch 40 member non-revolubly mounted relative to said shaft adapted to be thrown into engagement with said double clutch member whereby said shaft is rotated, a third clutch member revolubly mounted relative to said shaft 45 and relative to said double clutch member adapted to be thrown into engagement with said double clutch member; a second shaft revolubly mounted in said frame, gearing connecting said second shaft with said third 50 clutch member, means actuated by the rotation of said first-named shaft for raising said plow-beam, and means actuated by the rotation of said second shaft for releasing said plow-beam from its raised position.
